UNITED STATES PATENT OFFICE.

THOMAS J. GILLESPIE, OF HOMESTEAD, PENNSYLVANIA, ASSIGNOR OF ONE-HALF TO
HARRY J. TRIMBLE, OF PITTSBURGH, PENNSYLVANIA.

COLLAR-FASTENER.

1,353,739.

Specification of Letters Patent. Patented Sept. 21, 1920.

Application filed March 1, 1920. Serial No. 362,228.

To all whom it may concern:

Be it known that I, THOMAS J. GILLESPIE, a citizen of the United States, residing at Homestead, in the county of Allegheny and 5 State of Pennsylvania, have invented certain new and useful Improvements in Collar-Fasteners, of which the following is a specification.

This invention relates to new and useful 10 improvements in collar fasteners, more particularly to a substitute for the ordinary collar button used for securing the rear of the collar to the collar band of the shirt.

The objects of the invention are to provide 15 a device of the character stated, in a manner as hereinafter set forth, which will firmly hold a collar in the secured position, which lies flatly within the collar band of the shirt and the collar permitting the ready 20 adjustment of tie within the latter, which is simple in its construction and arrangement, strong, durable and efficient in its use, and comparatively inexpensive to manufacture.

To the accomplishment of these and such 25 other objects as may hereinafter appear the invention consists of the novel construction and arrangement herein specifically described and illustrated in the accompanying drawing wherein is shown an embodiment 30 of the invention, but it is to be understood that changes, variations and modifications may be resorted to which come within the scope of the claims hereunto appended.

In the drawing forming a portion of this 35 specification and wherein like numerals of reference designate corresponding parts throughout the several views:

Figure 1 is a fragmentary perspective view 40 of a neck band of a shirt having a collar fastener, in accordance with the invention, mounted therein.

Fig. 2 is a front or outer elevation of the fastener.

Fig. 3 is a view on line III—III, Fig. 1. 45 Fig. 4 is a perspective view of the collar fastener.

Referring in detail to the drawing, the 50 collar fastener in accordance with the invention and constructed from metal or other suitable material, comprises a flat body portion 1 curved longitudinally to conform to

the curvature of the human neck against which it is adapted to be used.

Formed integral with the lower edge of the body portion 1 and positioned adjacent each end thereof, is a depending clamping 55 arm 2 having a rounded lower end 3, which latter is curved slightly inwardly, as shown at 4 in Fig. 4, of the drawing.

Centrally disposed intermediate of the 60 clamping arms 2 and formed integrally with the lower edge of the body portion 1, is a depending collar securing element 5 comprising the narrow neck portion 6 and the enlarged flat rounded portion 7. The neck 65 portion 6 is slightly bent, as at 8, in a manner to position the upper portion of the enlarged portion 7 outwardly with respect to the outer face of the body portion 1, while the enlarged portion 7 inclines inwardly toward its lower end as clearly shown in Fig. 3 of the drawing.

The collar fastener is adapted to be mounted in the neck band of a shirt with only the enlarged portion 7, of the securing 75 element 5, inserted through the button-hole 9.

In securing a collar with the use of my improved fastener, the enlarged portion 7 thereof is inserted in the button-hole in the 80 rear of the collar. The construction of the securing element 5 with respect to the clamping arms 2 is such that a clamping action is set against the materials therebetween. The inwardly curved ends of the arms 2 facilitate the insertion of the fastener within 85 the shirt collar band.

A fastener of this construction will entirely eliminate the bulk of buttons ordinarily used for the same purpose and lies 90 flatly within the shirt collar band and collar, and will comfortably and securely hold the collar.

What I claim is:

1. A collar fastener comprising a body 95 portion having projecting from its lower edge a pair of arms each having its free end bent inwardly toward the body portion, said arms arranged inwardly with respect to the ends of the body portion, and a collar 100 retaining element projecting from the lower edge of and offset with respect to the body

portion, said element arranged between and spaced from said arms and having the lower portion thereof extending toward the body portion.

5. 2. A collar fastener comprising a body portion having projecting from its lower edge a pair of arms, said arms arranged inwardly with respect to the ends of the body portion, and a collar securing element projecting from and offset with respect to the

body portion, said element formed with a narrow neck at its upper terminus and having its lower portion enlarged and rounded and extending inwardly toward the body portion, said element arranged between and spaced from and of greater length than the arms. 12

In testimony whereof I affix my signature.

THOMAS J. GILLESPIE.
